ATTORNEY

UNITED STATES PATENT OFFICE.

PHILIP SUKERT, OF CHICAGO, ILLINOIS.

COMBINATION CIGAR-BOX MOISTENER AND COVER HOLDER.

Application filed December 24, 1925. Serial No. 77,665.

This invention relates to attachments for cigar boxes and more particularly to what I term a cigar box moistener and cover holder.

5 One of the main objects of the invention is to provide an attachment which can be readily applied to a cigar box of standard construction, such attachment being adapted to receive and retain a moistened strip of 10 absorbent material for supplying moisture to cigars within the box. A further object is to provide a device of this character having means cooperating therewith and with the cigar box for holding the lid or cover 15 of the box in open position. Further objects will appear from the detailed description.

In the drawings:

Figure 1 is a perspective view of the device as applied,

Figure 2 is a transverse sectional view through the device as applied, the box and the cover being broken away and partly shown in section,

25 Figure 3 is a sectional view taken substantially on line 3—3 of Fig. 2,

Figure 4 is a sectional view taken substantially on line 4—4 of Fig. 2.

The attachment includes an elongated box-like casing 1 formed of sheet metal and provided at each end of its rearward wall 1^a with a hook element 2. These hook elements are oppositely directed and are disposed for engagement about the end portions 30 of lid *a* of a cigar box A of known construction. Casing 1 is provided with a slot 3 in its lower wall and extending the full length thereof. The front wall 1^b of the casing is provided at each end with an extension which is bent upon itself to form 35 an arm 4 extending forwardly from the front wall of the casing. The forward portion of this arm is turned over upon itself to provide a supplemental arm 5 at the forward end of which is formed a tang 6 which extends inwardly from the supplemental arm 5 toward end wall *b* of box A. When the device is applied the supplemental arms 5 fit snugly against the outer face of the 45 end walls *b* of box A and the arms 4 rest upon the upper edges of the end walls of the box. The resiliency of arms 4 urges the arms toward the ends of the box so as to hold the tangs 6 in biting relation 50 with the walls *b*, it being understood that the tangs are forced into the end walls of

the box when the device is first applied. In this manner the arms 4 and supplemental arms 5 coact with casing 1 and hooks 2 to hold the cover or lid *a* of the box against 60 downward and forward movement, and the tangs 6 coact with the end walls *b* of the box to hold the cover *a* against rearward movement. The attachment thus serves to effectually hold the cover of the box in 65 open position. It is also to be noted that the cover fits snugly between the rearward arms of hooks 2 and the rearward wall 1^a of casing 1 so as to be embraced thereby in such manner that the box can be lifted by 70 the lid or cover *a* without danger of breaking the cover or of detaching the same from the box. This feature is of practical importance in that it is a common practice to remove boxes of cigars from display cases 75 by means of the covers of such boxes.

The casing 1 is adapted to receive a strip 7 of sponge or other suitable absorbent material. This strip of absorbent material is kept moistened with water and air entering 80 the casing through slots 8 at the ends thereof and flows over and through this strip so as to become saturated with the moisture therefrom, this moistened air flowing downwardly through the slot 3 into the box and 85 over the cigars therein which absorb the moisture from the air. In this manner the cigars are kept in a slightly moistened condition so as to prevent them from becoming dry and brittle.

90 What I claim is:

1. In a device of the character described, a casing adapted for reception of absorbent material and provided with an outlet opening, means for attaching the casing to the 95 cover of a cigar box with said cover in open position, and means for securing the casing to the box.

2. In a device of the character described, a casing having means for attaching the 100 same to a cigar box cover, arms extending forwardly from the casing, and means for securing the arms to the box.

3. In a device of the character described, a casing provided at its ends with rearwardly extending hook elements adapted 105 to fit snugly about the end portions of a cigar box cover, arms extending forwardly from the casing at the ends thereof, and means for securing the arms to the box.

4. In a device of the character described, a casing, means for attaching the casing to

a cigar box cover, arms extending forwardly from the ends of the casing and disposed to rest upon the upper edges of the end walls of the box, and supplemental arms 5 extending forwardly from the main arms and provided with tangs for engagement into the end walls of the box.

5. The combination with a cigar box body,

and a cover having hinged connection with the body, of a moistening device, means 10 slideable upon the cover for attaching the moistening device to the cover, and means extending away from the cover for attaching the moistening device to the side walls of the body.

PHILIP SUKERT.
